UNITED STATES PATENT OFFICE

FRANK G. NELSON, JR., OF MORGANTOWN, WEST VIRGINIA

GLASS WORKING APPARATUS

Application filed May 14, 1930. Serial No. 452,346.

This invention relates to a glass working apparatus, the general object of the invention being to provide means for the formation of footed ware from one piece of glass having a bulb at its lower end, with means for pressing the bulb to form the flat base for the article.

Another object of the invention is to provide means whereby the molds with the glass therein can be introduced into a tank of water by releasing a latch member which permits turning movement of the shaft to which the mold parts are attached so that the mold will drop into the tank placed under the same.

15 A further object of the invention is to provide means whereby the mold parts can be easily removed and substituted by new ones when desired.

This invention also consists in certain other 20 features of construction and in the combination and arrangement of the several parts, to be hereinafter fully described, illustrated in the accompanying drawings and specifically pointed out in the appended claims.

25 In describing the invention in detail, reference will be had to the accompanying drawings wherein like characters denote like or corresponding parts throughout the several views, and in which:—

30 Figure 1 is an elevation of the apparatus, with the parts in raised position.

Figure 2 is a vertical sectional view with the parts shown in raised position in full lines 35 and in lowered position in dotted lines.

Figure 3 is a front view with the parts in raised position.

Figure 4 is a section on line 4—4 of Figure 2.

40 Figure 5 is a section on line 5—5 of Figure 3.

Figure 6 is a section on line 6—6 of Figure 3.

45 Figure 7 is a sectional view through the mold parts with the article in section and

before the bulb at the lower end of the article is engaged by the plunger.

Figure 8 is a similar view, but showing the bulb part flattened into a base by the plunger member.

In these drawings, the letter A indicates a frame which is supported by the wheels 1 and 2 indicates a tank slidably arranged on the base part 3 of the frame. A platform 4 forms the top of the frame and a shaft 5 is journaled in the front uprights 6 of the frame. A small frame 7 has the depending parts 8 thereon which are fastened to the shaft and said small frame 7 carries the spaced rods 9 on which the cross head 10 is slidably supported, this cross head being adjusted on the rods by the threaded shaft 11 which passes through a threaded opening in the cross head and is swiveled in the frame 7 so that by turning the shaft, the cross head is moved on the rods. Tubular members 12 and 13 are slidably arranged on the rods 9 and are supported by the cross piece 10, the member 12 being non-rotatably supported, while the member 13 is rotatably supported. An arm 14 extends laterally from each tubular member and the mold sections 15 and 16 are removably attached to the outer ends of these arms 14 by the set screws 17. Thus both mold sections can be adjusted toward and away from the plate 7 and the section 16 can be moved toward and away from the section 15. A spring 18 tends to hold the section 16 in its outward position and a foot lever 19 is provided for holding the section 16 against the section 15, this lever passing through an opening formed in the platform. A spring 20 and a weight 21 are connected with the shaft 5 to counterbalance the weight of the mold sections, but the weight of the mold sections is such as to normally hold the parts with the mold in the tank, as shown in dotted lines in Figure 2. The weight 21 is adjustable on its arm 22 which is attached to one end of the shaft, the

spring 20 being attached to the other end and to a part of the upper part of the frame.

A pedal 23, pivoted at 24, and arranged at one side of the platform, is connected to an arm 25 on the shaft 5 by a link 26 so that by depressing this pedal, the parts will be moved to raised position with the mold in vertical position, as shown in full lines in the figures. A latch bar 27, connected with the shaft 5, is adapted to engage a keeper member 28 on an upright lever 29 to hold the parts in raised position, said lever being pivoted at its lower end to the lower part of the frame, as shown at 30, and having its upper end engaged by a spring 31 which tends to hold the keeper member 28 under the latch member 27. The upper end of the lever 29 projects above the platform so that it can be pushed outwardly to release the latch 27 from the keeper 28. The upper end of the lever 29 is arranged adjacent the free end of the pedal 23 so that both these parts can be manipulated by the same foot.

A yoke member 32 is pivoted on the shaft 5 and is located between the limbs of the member 8 and a rod 34 passes through the yoke member and is fastened to the bight thereof intermediate the ends of the rod. A weight 35 is adjustably connected with the rear end of the rod 34 and a shoe 36 is connected with the front end of the rod. This shoe engages the lower end of a stem 37 slidably arranged in a tubular part 38 depending from the front end of the member 7 and a presser head 39 is carried by the upper end of the stem 37 and is arranged under the mold. A rod 40 passes through a hole in the member 7 and through a bushing 41 carried by the member 7 and has an enlargement 42 at its lower end which rests on the bar 34. The upper end of the rod 40 is engaged by a shoe 43 on the lower end of a plunger rod 44 when the same is depressed against the action of its spring 45 by the operator placing his foot on the head 46 of the plunger rod. Thus when this plunger rod is depressed, the rod 40 is pressed against the rod 34, so that the rod 34 is rocked and its weighted end raised and its front end lowered, thus permitting the stem 37 and its head 39 to move downwardly under the action of gravity. When pressure is released from the head 36, the weight 35 will move the rod 34 to its normal position and thus raise the stem 37 and its head 39 so that said head 39 will press upon the spherical part *a* of the article A in the mold and thus flatten the spherical part, as shown in Figure 8, so as to form a base for the article.

As will be understood, when the parts are in raised position, the pedal lever 19 is depressed so as to move the mold section 16 against the section 15 and the plunger rod 44 is depressed to permit the head 39 to drop, thus leaving the lower end of the mold open. The article is then blown in the mold in the

ordinary manner and by leaving the lower end open, the spherical part *a* will be formed, as shown in Figure 7. The foot is then removed from the head 46, so as to permit the weight 35 to cause the rod 34 to raise the stem 37 and its head 39 to flatten the spherical part *a*, as shown in Figure 8. The plunger 44 is then depressed to permit the head 39 to move away from the mold and then the pedal lever 19 is released so that the mold will open and the article can be removed therefrom. The lever 29 is then moved outwardly to cause the keeper 28 to release the latch 27 and then the pedal 23 is depressed so as to rock the shaft 5 and cause the mold sections to enter the water in the tank.

As will be seen, the cross piece 10 can be adjusted on the rods 9 by the screw shaft 11 so as to adjust the mold sections in relation to the head 39 to form different sizes of bases on the article and by removably supporting the tank, the same can be removed for cleaning purposes. The stem of the article is hollow and it may be formed of various colors and by using different shapes of mold sections, various designs of stems can be formed.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A device of the class described comprising a frame, a water tank removably arranged in the bottom of the frame, a shaft journaled in the frame above the tank, a small frame carried by the shaft, rods carried by the small frame, a member slidably arranged on each rod, an arm on each member, a mold section removably attached to each arm, a plunger member carried by the small frame, a weighted lever pivoted to the shaft and normally holding the plunger member against the bottom of the mold, foot operated means for moving the weighted lever downwardly to cause the plunger member to move away from the mold, means whereby the mold sections can be separated, latch means for normally holding the shaft in a position with the molds in a vertical position and means for rocking the shaft when the latch means are released to permit the mold sections to drop into the tank.

2. A device of the class described comprising a frame, a water tank removably arranged in the bottom of the frame, a shaft journaled in the frame above the tank, a small frame carried by the shaft, rods carried by the small frame, a member slidably arranged on each rod, an arm on each member, a mold section removably attached to each arm, a plunger member carried by the small frame,

a weighted lever pivoted to the shaft and normally holding the plunger member against the bottom of the mold, foot operated means for moving the weighted lever downwardly
5 to cause the plunger member to move away from the mold, means whereby the mold sections can be separated, latch means for normally holding the shaft in a position with the molds in a vertical position, means for
10 rocking the shaft when the latch means are released to permit the mold sections to drop into the tank and counterbalancing means connected with the shaft.

In testimony whereof I affix my signature.
